WINDOW SASH WEATHERSTRIP

Robert J. Deisenroth and Carl E. Sigsbee, Elkhart, Ind., assignors to Excel Corporation, Elkhart, Ind., a corporation of Indiana

Filed Jan. 2, 1964, Ser. No. 334,984
9 Claims. (Cl. 49—439)

This invention relates to a window sash weatherstrip, and more particularly to a window sash weatherstrip fabricated from a plastic material and which will effectively serve as a weatherstrip when mounted on a sliding sash.

The window sash weatherstrip of the present invention is particularly useful in connection with sliding windows such as those provided in buses, automobiles, aircraft and other vehicles.

In the past, window sash weatherstrips have been principally fabricated from materials such as wool or synthetic organic filament pile (made from such plastics as nylon, vinyl, polyesters, polyethylene and polypropylene), cloth, felt, flocked rubber and various rubberized fabrics. It has been considered desirable to substitute rigid plastic for these materials because rigid plastic has several properties which are desirable in a weatherstrip. For example, rigid plastic is impervious to moisture and gases; it is durable; easily adapted to mass production manufacture and has a relatively low cost. It has, however, been difficult to utilize rigid plastic for a weatherstrip because it is hard to obtain a good seal between the plastic and the contacting member to prevent the passage of air and moisture and also to obtain low-friction sliding action between the plastic and the contacting member.

One solution to this problem is disclosed in United States Patent 3,018,525. The present invention provides an alternate solution in which the amount of plastic which must be used is reduced approximately one-half, thus resulting in a considerable manufacturing saving.

It is, therefore, an object of this invention to provide a window sash weatherstrip fabricated from a rigid plastic material.

Another object of the invention is to provide a window sash weatherstrip which will form a weather-tight seal with a contacting member.

An additional object of the invention is to provide a window sash weatherstrip which requires only approximately one-half as much material as prior art weatherstrips require.

Another object of the invention is to provide a window sash weatherstrip which will firmly engage the sash and at the same time has structure for sealing engagement with a guide channel, the weatherstrip structure permitting use thereof in channels having relatively large dimensional tolerances.

Other objects of this invention will appear in the following description and appended claims, reference being had to the accompanying drawings forming a part of this specification wherein like reference characters designate corresponding parts in the several views.

In the drawings:

FIGURE 1 is a front elevational view of a sliding window construction in which one embodiment of the window sash weatherstrip of the invention is incorporated;

FIGURE 2 is a sectional view taken substantially along the line 2—2 of the FIGURE 1, looking in the direction of the arrows; and

FIGURE 3 is a partial front elevational view of the sliding sash forming a part of the window construction of FIGURE 1.

Before explaining the present invention in detail, it is to be understood that the invention is not limited in its

2

application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring to FIGURE 1, a window structure 10 of the type commonly employed in bus construction is illustrated. The window construction 10 comprises a generally rectangular window frame 12 having left and right jambs 14, 16 connected together at their upper and lower ends by, respectively, a header 18 and a fixed sash 20. The frame 12 is mounted in an opening 22 provided in vehicle body structure 24.

Mounted in the frame 12 are a pair of generally rectangular sashes 20, 26. The upper sash 26 is slidable and the lower sash 20 is fixed. As above-mentioned, the lower sash serves to connect the lower ends of frame jambs 14, 16.

The slidable sash 26 comprises left and right stiles 28, 30, joined together at their upper and lower ends by, respectively, a top rail 32 and a meeting or bottom rail 34. A lock 36, 38 is provided on each upper corner of the sash 26 on the interior surface or face thereof.

The lower sash 20 comprises left and right stiles 40, 42 joined together at the upper and lower ends by, respectively, a meeting or top rail 44, and a bottom rail 46. Each sash is provided with a window pane element 48, 50.

The jamb structure is illustrated in FIGURE 2. As will be noted, the jamb 16 is constructed from two members, an elongated L-shaped member 52 and an elongated U-shaped member 54. The L-shaped member may be fabricated from any desired metallic material, such as, for example, steel or aluminum. However, the channel member 54 should be fabricated from a relatively high strength material, such as steel, in order to be capable of forming lock racks and withstanding the stresses of the sash which it supports. The U-shaped member 54 is secured to one leg or flange 56 of the L-shaped member in any suitable manner, such as by riveting.

As will be noted, the legs 58, 60 of the U-shaped member 54 are parallel to the leg 62 of the L-shaped member 52 to thus form a pair of channels or tracks 64, 66. The upper portion of the channel 64 forms a track for the window lock 38, while the lower portion is utilized to fixedly mount the lower sash 20. The movable sash 26 is slidably received in the other channel 66. Interned 50 lips 67, 69 are formed on the outer ends of legs 60, 62 to retain the movable sash 26 in place.

The weatherstrip 68 of the present invention is secured to a movable sash 26 and is received and retained in the channel 66.

The weatherstrip 68 is a continuous strip fabricated from an organic polymeric material. The plastic should have such physical properties as impermeability to moisture and air, toughness, stability, and a low coefficient of friction. The material should be flexible and rigid as it 60 must be able to yield under pressure and return to its original shape upon the release of pressure. A preferred organic polymeric material is propylene. Additives, such as pigments and fillers as commonly used in the plastic art may be employed with the plastic material. A 65 lubricant may be impregnated into the outer surface of the plastic material to reduce its coefficient of friction. The continuous strip may be formed by any well-known extrusion process. In extruding this strip, it is desirable to keep the surface as smooth as possible in order to reduce the coefficient of friction and prevent sticking and squeaking when in sliding contact with a contacting member.

As may best be seen in FIGURE 2, the weatherstrip 68 has a channel-shaped cross-sectional contour comprising a bottom wall 70 and a pair of side walls 72, 74 extending angularly outwardly therefrom. The outer end portions 76, 78 of the side walls extend straight outwardly in parallel fashion and are substantially perpendicular to the plane defined by the bottom wall 70. A plurality of spaced longitudinally extending ribs 80, 82, 84 are provided on each of the outer surfaces of the bottom wall 70 and side wall portions 76, 78 to result in reduced friction and smooth sliding with the inner surfaces of 56, 62 and 60, respectively, of jamb 16.

As a result of the outward angle of the side walls 72, 74, the side wall portions 76, 78 are spaced farther apart than are the side walls at the point of their attachment 86, 88 to the bottom wall 70.

A longitudinally extending circular channel 90 is provided within the channel defined by the bottom wall 70 and side walls 72, 74. The channel 90 is attached to the inner surface of the bottom wall 70 by means of a longitudinally extending web 92. The channel 90 serves to receive the sash tongue 94 to thus secure the weatherstrip to the sash 26. The outer ends 96, 98 of the channel 90 side walls are curved outwardly to conform to the configuration of the bulb-shaped portion 95 of the sash tongue 94. This arrangement prevents separation of the weatherstrip and sash tongue and provides a simple attachment of the weatherstrip to the sash.

It will be noted that the channel 90 has an interior radius which is slightly larger than the exterior radius of the bulb portion 95. This relatively loose fit permits the channel 90 to receive sash tongues which may be of slightly varying dimensions. However, the reversely curved ends 96, 98 of the channel 90 are closer together than the neck portion 97 of the tongue 94 to snugly engage the neck portion and form a fluid-tight seal.

The stile 30 of the sash 26 is channel-shaped to receive the window pane 48 which is glazed therein by a plastic glazing strip 100. The web 102 of the stile 30 is fabricated to form the sash tongue 94 comprising bulb-shaped portion 95 having the neck portion 97 from which extends spaced-apart longitudinally extending wall portions 104, 106. The sash tongue 94 is thus a hollow member. This tongue shape provides means for attaching the weatherstrip 68 lengthwise thereon. As will be noted in FIGURE 3, each end 108, 110 of the bulb portion 95 is upset to thus firmly engage the ends of the channel 90 and prevent sliding of the weatherstrip 68 along the sash tongue.

In assembling the window construction 10, the sash 26 may be slid into the jambs 14, 16 prior to mounting of the header 18. The weatherstrip 68 is, of course, previously secured to the sash tongue 94 by inserting the bulb portion 95 into the channel 90. As will be appreciated, the side walls of the channel 90 are relatively flexible and will permit insertion of the sash tongue 94 and will subsequently resume their original position as shown in FIGURE 2 with ends 96 and 98 gripping the neck 97 to form a weather seal.

In operation of the invention, the slideable sash 26 may be moved up and down the channel 66 with the ribs 80, 82, 84 maintaining sealing engagement with the inner surfaces of the legs 60, 62 and flange 56. The ribs 80, 82, 84 also provide for line contact with the channel surfaces to thus result in reduced friction and smooth sliding. The end portions 76, 78 of the weatherstrip side walls 72, 74 are spaced apart a distance somewhat more than the spacing of the interior surfaces of the channel 66 side walls. The weatherstrip side walls 72, 74 deflect inwardly when mounted in the channel 66 to form a weather-tight seal with the channel interior surfaces. A deviation in the size of the channel will not require the use of a different size weatherstrip and still a seal is always provided. The weatherstrip 68 will perform adequately in channels which have a considerable dimensional variation.

As will be appreciated, it is difficult to maintain close tolerances when fabricating the jambs 14, 16. The use of the weatherstrip 68 permits wider variations than would otherwise be permissible with resultant reduced manufacturing costs in terms of quality control. This result is due to the fact that the weatherstrip channel 90 is independent of the side wall construction 72, 74. Thus, the side walls 72, 74 are deflected to engage the interior surfaces of the jambs 14, 16, while the channel 90 independently engages and forms a tight seal with the sash tongue 94. An additional advantage of the invention resides in the fact that it is only necessary that the weatherstrip be equal in length to the length of the sash tongue 94. In most prior art constructions, weatherstrips have been mounted in the window jamb rather than on the sash. In prior art constructions it is consequently necessary to provide a weatherstrip having a length equal to the length of the jamb.

Having thus described our invention, we claim:

1. A weatherstrip for a sliding window construction comprising an elongated member fabricated from an organic polymeric material, said member being generally channel-shaped in cross-section and having outwardly angled flexible side wall portions which are deflectable for substantially leak-free sliding contact of the free end portions thereof with the interior wall surfaces of a receiving channel, and attaching means formed within the weatherstrip channel and integrally therewith, said attaching means including wall means for pressure engagement with and for leak-free securement to a window sash, the location of integration of said attaching means with the weatherstrip channel being spaced from the outermost portions of the side walls to permit flexing of said outermost portion.

2. A weatherstrip for a sliding window construction, the weatherstrip being for attachment to the stile of a window sash for mounting the sash in a receiving channel, said weatherstrip comprising an elongated member fabricated from an organic polymeric material, said member being generally channel-shaped in cross-section and having outwardly angled flexible side walls, said side walls at their widest spacing exceeding the width of the intended receiving channel for substantially leak-free sliding contact of the free end portions thereof with the interior wall surfaces of the receiving channel, and attaching means formed within the weatherstrip channel and integrally therewith, said attaching means including wall means for pressure engagement with and for leak-free securement to a window sash, the location of integration of said attaching means with the weatherstrip channel being spaced inwardly from the widest spacing of the channel side walls to permit flexing of the portion of the side walls beyond said location of integration.

3. A weatherstrip for a sliding window construction comprising an elongated member fabricated from an organic polymeric material, said member being generally channel-shaped in cross-section and having a bottom wall with outwardly angled resilient side walls which are deflectable for substantially leak-free sliding contact of the free end portions thereof with the interior wall surfaces of a receiving channel, said bottom wall having a longitudinally extending rib structure on the exterior surface thereof for sealing engagement with the interior surface of the bottom wall of the receiving channel, and attaching means formed within the weatherstrip channel and integrally therewith, said attaching means including wall means for pressure engagement with and for leak-free securement to a window sash, the location of integration of said attaching means being spaced inwardly from the outermost portions of the side walls to permit flexing of the outermost portions of the side walls beyond said location of integration.

4. A weatherstrip for a sliding window construction comprising an elongated member fabricated from an organic polymeric material, said member being generally

channel-shaped in cross-section and having a bottom wall with outwardly angled flexible side walls, the side walls each having a longitudinally extending rib structure on the exterior surfaces thereof for substantially leak-free sliding contact of the free end portions of the side walls with the interior wall surfaces of a receiving channel, and attaching means formed within the weatherstrip channel and integrally therewith, said attaching means including wall means for pressure engagement with and for leak-free securement to a window sash, the location of integration of said attaching means with the weatherstrip channel being spaced inwardly from the outermost portions of the side walls to permit flexing of the portion of the side walls beyond said location of integration.

5. A weatherstrip for a sliding window comprising an elongated member fabricated from an organic polymeric material, said member being generally channel-shaped in cross-section and having a bottom wall with side walls extending therefrom, the first portion of the side walls being outwardly angled and the terminal portion of the side walls being substantially parallel to each other and perpendicular to the plane of the bottom wall, said walls being deflectable for substantially leak-free sliding contact of the terminal portions thereof with the interior wall surfaces of a receiving channel, and attaching means formed within the weatherstrip channel and integrally therewith for leak-free securement to a window sash, the location of integration of said attaching means with the weatherstrip channel being spaced inwardly from the outermost portions of the side walls to permit flexing of the portion of the side walls beyond said location of integration.

6. A weatherstrip for a sliding window construction comprising an elongated member fabricated from an organic polymeric material, said member being generally channel-shaped in cross-section and having outwardly angled flexible side walls which are deflectable for substantially leak-free sliding contact of the free end portions thereof with the interior wall surfaces of a receiving channel, and channel-shaped attaching means formed within the weatherstrip channel and integrally therewith for leak-free securement to a window sash, the location of integration of said attaching means with the weatherstrip channel being spaced inwardly from the outermost portions of the side walls to permit flexing of the portion of the side walls beyond said location of integration.

7. A weatherstrip for a sliding window construction comprising an elongated member fabricated from an organic polymeric material, said member being generally channel-shaped in cross-section and having a bottom wall with outwardly angled resilient side walls which are deflectable for substantially leak-free sliding contact of the free end portions thereof with the interior wall surfaces of a receiving channel, an attaching channel formed within the weatherstrip channel for securement to a window sash, and a web extending between said attach-

ing channel and the bottom wall securing the attaching channel to the bottom wall.

8. A weatherstrip for a sliding window construction comprising an elongated member fabricated from an organic polymeric material, said member being generally channel-shaped in cross-section and having outwardly angled flexible side walls which are deformable for substantially leak-free sliding contact with the interior wall surfaces of a receiving channel, and a circular attaching channel secured within the weatherstrip channel and integrally therewith for leak-free securement to a window sash, the location of integration of said attaching channel with the weatherstrip channel being spaced inwardly from the outermost portions of the side walls to permit flexing of the portion of the side walls beyond said location of integration.

9. A weatherstrip for a sliding window construction comprising an elongated member fabricated from an organic polymeric material, said member being generally channel-shaped in cross-section and having a bottom wall with side walls extending therefrom, the first portion of said side walls being outwardly angled and the terminal portions thereof being substantially parallel to each other and perpendicular to the plane of the bottom wall, said side walls being flexible for substantially leak-free sliding contact of the terminal portions thereof with the interior wall surfaces of a receiving channel, and an attaching channel formed within the weatherstrip channel for securement to the tongue of a window sash, said attaching channel being separate from the outermost portions of the side walls to permit flexing of the side walls, said attaching channel having interior dimensions slightly larger than the exterior diameter of the intended sash tongue portion to be received therein, the attaching channel having a re-entrant opening smaller than the intended sash tongue portion to be located therein for leak-free contact therewith.
